UNITED STATES PATENT OFFICE.

GEORGE H. PETERSON, OF BROOKLYN, NEW YORK, ASSIGNOR TO AMERICAN TELEPHONE AND TELEGRAPH COMPANY, A CORPORATION OF NEW YORK.

TELEPHONE SYSTEM.

Application filed November 22, 1924. Serial No. 751,615.

This invention relates to telephone systems and more particularly to trunk circuits.

The invention is shown as applied to a system employing automatic switch mechanisms for extending calling subscribers' lines to tandem operators' positions, provided with apparatus for registering and visually indicating the numbers of the wanted lines. From these tandem positions the calls are 10 further extended over what are called straightforward trunks.

Upon the initiation of a call by a subscriber a signal is displayed before the tandem operator who then actuates the display 15 key associated with the displayed signal thereby causing the number dialed by the subscriber to be displayed. After observing the wanted number the tandem operator inserts the plug end of the calling trunk into 20 an idle outgoing straightforward trunk jack and passes the necessary information to the distant straightforward B operator who thereupon further extends the call in any suitable manner.

25 In the patent to G. H. Peterson No. 1,566,345, issued December 22, 1925, such an arrangement is fully described wherein the actuation by the operator of a positional release key, after the number has been 30 passed to the distant B operator, extinguishes the trunk signal, retires the display, and disconnects the operator's telephone set.

An object of this invention is to automatically disconnect the operator's telephone set 35 from a first trunk and connect it to a second trunk in case the second trunk, on which a call may be waiting, is plugged up to an outgoing trunk.

The principal feature of the invention 40 therefore resides in the provision of a positional relay arrangement whereby, responsive to the insertion of a second incoming trunk plug in an outgoing trunk jack while the operator's telephone is connected to a 45 plugged up first trunk, the operator's telephone is automatically released from the first trunk and connected to the second trunk.

Other objects and features will be apparent 50 from the following description when read in connection with the drawings.

The invention is illustrated by the accompanying drawing wherein the subscriber's station X in addition to being provided with 55 the usual substation apparatus is also pro-

vided with an impulse sending device Y. The subscriber's line is automatically connected to a tandem operator's position, shown between the broken vertical lines *aa'* and *bb'*, by means of automatic switches N 60 over trunk TK, one of said switches selecting an idle trunk to sender Q and this trunk in turn being extended to the trunk TK terminating at the tandem operator's position in the plug 33 adapted to be inserted in jack 65 34 associated with a trunk extending to a B operator's position indicated to the right of the broken line *bb'*.

Associated with the trunk TK at the tandem operator's position is a display board Z 70 provided with the usual display lamps or indicators. These lamps or indicators are operated by impulses transmitted from the sender Q in which is stored up the impulses transmitted by the sending device Y at the 75 subscriber's station X. The automatic switch N, sender Q and the display board circuits are fully disclosed in the patent to A. E. Lundell and E. H. Clark, 1,464,084, and will therefore not be described in detail 80 in this specification. The B operator's telephone set and apparatus shown in the outline 100 is fully disclosed in a copending application, Serial No. 738,488, filed September 18, 1924, in the names of Messrs. R. S. 85 Bailey and E. B. Broe.

The operation of the system is as follows:

The sender Q is automatically connected to a subscriber's line upon the initiation of a call whereupon the connection is extended 90 to the tandem operator's trunk TK which terminates in the plug 33. When the call is extended to the sender Q the manipulation of the sending device Y by the subscriber transmits impulses corresponding to the 95 number of the wanted line. These impulses are received by and stored up in the sender Q. When the connection is extended to the trunk the circuit of relay A is completed by the closure of a circuit in the automatic 100 equipment. The operation of relay A completes the circuit of relay B as follows: Battery, outer right normal contacts of relay K, winding of relay B, inner right normal contacts of relay D, and to ground at 105 the alternate contacts of relay A. The operation of relay B completes the circuit of lamp L as follows: battery, lamp L, and outer right alternate contacts of relay B to ground. Relay B in operating also locks 110

itself to battery at its inner right alternate contacts. This relay is now held independent of the relay K. The lighting of lamp L indicates to the tandem operator that a call 5 is waiting and she then presses the display key M which closes a circuit for the operation of relay I as follows: ground (not shown) in the display board Z, conductor 6, contacts of key M, left alternate contacts 10 of relay B, left-hand winding of relay I and to battery (not shown) in the display board circuit. Relay I in operating locks itself to ground at its right-hand alternate contacts under control of relay H in an obvious 15 circuit and at its outer left alternate contacts prepares a circuit for the operation of relay R. At its inner left alternate contacts relay I completes an obvious circuit for the energization of relay K, the operation of 20 which completes the circuit of relay C as follows: battery, inner right alternate contacts of relays B and K and winding of relay C to ground. Relay C in operating connects battery at its right-hand contacts to 25 conductor 10 extending to the winding of relay but as the other terminal of the winding D is likewise connected to battery, this relay is short circuited and therefore prevented from operating at this time. The 30 operation of relay C also completes the previously prepared circuit for relay R as follows: battery, left-hand contacts of relay C, winding of relay R, outer left alternate contacts of relay I to ground (not shown) in 35 the display board circuit Z. The operation of relay R opens the trunk conductors at its upper and lower alternate contacts and at its upper and lower alternate contacts connects the trunk and the associated sender Q 40 to the display board Z thereby causing, in a well understood manner, the operation of the sender which thereupon transmits the stored up impulses to operate the indicators in the display equipment to display the 45 number of the wanted line.

When relay R operates to open the trunk, it thereby opens the circuit of relay A which relay in turn removes ground from the winding of relay B, which in turn releases. 50 Relay B in restoring opens its inner right alternate contacts thereby removing battery from the original energizing circuit of relay C. Relay C, however, remains operated as a holding circuit now exists over conductor 55 10 and the winding of relay D to battery. Relay D operates at this time due to the disconnection of the battery from its lower right-hand terminal and, in operating, closes an obvious energizing circuit for relay D. 60 The release of relay B, with relay K operated, transfers lamp L from the steady ground at the outer right alternate contacts of relay B to the interrupted ground through interrupter 50. This circuit can be traced from battery, lamp L, outer right

normal contacts of relay B, left alternate contacts of relay K through interrupter 50 to ground. This causes lamp L to flash thereby indicating to the operator that the sender Q has been connected to the display 70 board Z and after the number has been displayed, it indicates which trunk transmitted the number.

After the code impulses have all been received, ground is removed from conductor 75 5 in the display cord circuit thereby opening the circuit of relay R, which relay then releases and disconnects the trunk from the display board and connects them to the conductors 26 and 27.

When relay R restores, assuming the calling subscriber's receiver is still off the hook, relay A is again energized over the calling trunk. The operation of relay A at this time connects ground to the inner right 85 contacts of relay D, and thence over conductor 10 and the right-hand contacts and winding of relay C, thereby short circuiting it and causing it to release. Relay D does not release however, and it will be held by this 90 same ground supplied by relay A. This relay is, therefore, now under control of relay A.

The tandem operator upon noting the 95 number of the wanted line tests for an idle trunk extending to an exchange in which the wanted line is located. Assuming that the trunk terminating in jack 34 is idle, plug 33 is inserted therein thereby completing the circuit of relay E as follows: battery, 100 winding of relay E, sleeve contacts of plug 33 and jack 34 and winding of relay 35 to ground. Relay E in operating completes a circuit for the operation of relay G, as follows: battery, resistance WL, back normal 105 contacts of relay F, conductor ST, contacts 19 and winding of relay G, lowermost alternate contacts of relay E, alternate contacts of relay D1 and to ground at the left-hand normal contacts of relay H. Relay E in operating also opens at its uppermost normal 110 contacts the connection between the tip of the plug and the busy test lead BT extending to the operator's telephone set and at its uppermost alternate contacts connects conductor 40 through to the tip of the plug. Relay E in operating also prepares, at its inner lower alternate contacts, a circuit for supervisory lamp P which circuit is, however, open at the outer right contacts of relay D and therefore, this lamp is not lighted at this time. Also, when relay E operates, it removes a short circuit from around the energizing winding of relay H thereby preparing 120 this relay for operation, which will be 125 later discussed.

When relay G operates, it opens at its contacts 45 and 46 the connection between the trunk conductors 26 and 27, and the conductors 40 and 41 and closes at its alternate 130

contacts 47 and 48 a connection between the operator's telephone, not shown, and the conductors 40 and 41 extending through to the tip and ring contacts of the plug and jack. It should be noted that relay J is also connected in parallel with resistance WL in the operating circuit for relay G but relay J will not operate in this circuit due to the very low value of resistance WL. 10 It may be mentioned, however, that resistance WL is inserted in the circuit for battery protection reasons only, and performs no other useful function.

Relay G in operating, locks to battery in series with relay F in an obvious circuit whereupon relay F operates, thereby disconnecting battery, through resistance WL, from the ST lead.

The operator's telephone set is now connected to the outgoing straightforward trunk circuit extending to the operator's telephone at the B operator's position, whereupon the tandem operator passes the number, displayed by the indicator Z, to the B operator. 20 It should be noted that, as relay G is operated, the talking conductors extending back of the calling subscriber, are disconnected from the conductors 40 and 41, and therefore, the calling subscriber does not hear the tandem operator pass the details of the call to the straightforward B operator. As soon as the call has been passed, however, it is necessary for the calling subscriber to be connected to the outgoing 30 trunk and also that the tandem operator's telephone set be disconnected. Both these operations will be effected by the release of relay G which may be caused either by the manual operation of release key RK, or automatically by the insertion of a second incoming trunk, in another straightforward trunk jack corresponding to the jack 34 in conjunction with the operation of the display key associated with the second incoming trunk.

We will first assume that the tandem operator has passed the call and that no calls are waiting on any of the other incoming trunks terminating at her position. Under 40 these conditions the operator will operate release key RK, thereby connecting ground to conductor LO and causing the operation of relay H which as before mentioned, is now in readiness to be operated. The circuit for the operation of relay H can be traced from battery through its energizing winding, and also its non-inductive winding 51, conductor 52, lowermost alternate contacts of relay G, conductor LO, and to ground at key RK. Relay H, in operating, locks itself up at its left-hand alternate contacts under control of the E relay. That is, it is under the control of relay E in the sense that when 50 plug 33 is removed from jack 34, relay E will release, thereby connecting battery to the upper terminal of relay H and again short-circuiting it. The operation of relay H also removes the operating ground for relay G and therefore, this relay releases 70 thereby disconnecting the operator's telephone set and connecting the conductors extending to the calling subscriber through to the tip and ring of the plug which are connected to the outgoing trunk. The operation of relay H also releases relay I which in its turn releases relay K. Relay K in releasing, opens the flashing circuit for lamp L. The removal of ground at the right-hand contacts of relay H, which causes 80 the release of relay I, also removes ground from the lead 5 to the display board Z and thereby releases the display mechanism to wipe out the number. The arrangement for holding relay H operated until the plug has 85 been removed renders the display key M ineffective to cause the display of a second number in the event that the trunk TK is reselected after the first calling subscriber disconnects and before the plug 33 has been 90 removed from jack 34.

In the foregoing, the manual release of the operator's telephone and the connection through of the calling trunk, has been described.

It will now be assumed that before the tandem operator has finished passing the details of a call, a second trunk lamp, corresponding to lamp L, associated with another of the incoming trunks corresponding to 100 TK, lights thereby indicating that a second call is awaiting attention. Under these conditions in accordance with a feature of this invention it is unnecessary for the operator to operate the key RK in order to release 105 her telephone and connect the first trunk through, as this will be performed automatically in response to the insertion of the plug of the second trunk into another of the outgoing straightforward trunk jacks corresponding to jack 34, and the operation of 110 the display key associated with the second trunk. The arrangement for accomplishing this feature will now be described.

At the left of the drawing and within the 115 rectangle surrounded by a broken line is common positional equipment which consists of the previously mentioned relays J and H and the release key RK.

It will be remembered that when relay G 120 of the first trunk was operated, relay F operated in the circuit thereby removing battery, through resistance WL, from the lead ST. Battery in series with the high resistance winding of the J relay is, however, connected to the windings of all the other G relays at the position. When the second trunk plug is inserted in the selected outgoing trunk jack, and, providing the associated D relay is operated, a circuit is 125 130

- closed from battery, through the J relay, over conductor ST, normal contacts and winding of the G relay of the second trunk, lower alternate contacts of the E relay of the second trunk which is now operated, due to the insertion of the associated plug in the jack and over the alternate contacts of the associated D1 relay to ground, over the normal contacts of the associated H relay.
- 5 The G relay of the second trunk will not operate in this circuit, however, due to the high resistance of relay J but that relay operates, thereby connecting ground at its alternate contacts over the inner right-hand alternate contacts of relay F and conductor LO, lowermost alternate contacts of the G relay of the first trunk, conductor 52 and the non-inductive and the operating windings of relay H to battery thereby causing 10 this relay H to operate, as before described, in connection with the manual operation of key RK, to release the operator's telephone set and connect the first trunk through to the outgoing line. Relay H of the first trunk 15 is operating, releases the G relay of that trunk as previously described, thereby releasing relay F of the positional circuit. Relay F, in releasing, connects battery in series with low resistance WL to the ST lead thereby shunting relay J and causing it to release and at the same time supplies sufficient current for the operation of the G relay of the second trunk to cause its operation.
- 20 30 It will therefore be noted that under the above conditions, the telephone set is automatically transferred from the first trunk to the second trunk merely by the insertion of the second trunk in an outgoing jack.
- 35 40 What is claimed is:
1. In a telephone exchange system, an operator's position including an operator's telephone set, first and second plug-ended line circuits incoming to said position, a plurality of outgoing lines at said position, means jointly responsive to a call on said first incoming line, the operation of a key and the connection of said calling line with one of said outgoing lines for connecting 45 said operator's telephone to the seized outgoing line, and means automatically responsive to a call on said second incoming line and its connection with another of said outgoing lines before said first incoming line is disconnected for transferring said operator's telephone from said first seized to said second seized outgoing line.
  2. In a telephone exchange system, an operator's position including an operator's telephone set, a plurality of line circuits incoming to said position, a plurality of outgoing lines extending from said position, means responsive to the connection of a calling one of said incoming lines to one of said 55 outgoing lines for connecting said telephone set to said outgoing line to the exclusion of the outgoing end of said incoming line, and means automatically responsive to a call on another of said incoming lines and its connection with another of said outgoing lines, before said first incoming line is disconnected, for transferring said telephone set from said first to said second outgoing line.
5. In a telephone exchange system, an operator's position including a telephone set, a plurality of incoming lines terminating at said position, a plurality of outgoing lines extending therefrom, means responsive to the connection of a calling one of said incoming lines with one of said outgoing lines for connecting said telephone set thereto, and means responsive to the connection of a second calling line with a second outgoing line before said first connection is broken down, for transferring said telephone set from said first to said second connection.
6. In a telephone exchange system, an operator's position including a telephone set, a plurality of incoming lines terminating at said position, a plurality of outgoing lines extending therefrom, means responsive to the connection of a calling one of said incoming lines with one of said outgoing lines for connecting said telephone set to said outgoing line to the exclusion of the calling end of said incoming line, and means responsive to the connection of a second calling line with a second outgoing line before said first connection is broken for transferring said telephone set from said first outgoing line to said second outgoing line.
7. In a telephone exchange system, an operator's position including a telephone set, a plurality of incoming lines terminating at said position, a plurality of outgoing lines extending therefrom, means responsive to the connection of a calling one of said incoming lines with one of said outgoing lines for connecting said telephone set exclusively to the incoming end of said calling line, and means responsive to the connection of a second calling line with a second outgoing line, before said first line is disconnected, for transferring said telephone set from the incoming end of said first calling line to the incoming end of said second calling line.
8. In a telephone exchange system, a call indicator operator's position including an operator's telephone set, a plurality of line circuits incoming to said position, a plurality of outgoing line circuits extending from said position, a number display device at said position, and operator controlled means for causing said device to indicate the number wanted by a calling one of said incoming lines, means jointly responsive to the operation of said operator controlled means, and the connection of said calling line with one of said outgoing lines for connecting said operator's telephone set to the

- seized outgoing line to the exclusion of the incoming line, and means automatically responsive to the connection of a second calling incoming line to another of said outgoing lines during the existence of the said connection between said first incoming line and said outgoing line, for transferring said operator's telephone set from said first seized to said second seized outgoing line to the exclusion of said second incoming line.
7. In combination, a first and a second incoming trunk, an operator's telephone set, a relay individual to each incoming trunk, a plurality of outgoing trunk jacks, means controlled by its associated individual relay when one of said trunk plugs is inserted in one of said jacks for disconnecting the talking conductors of said trunk from the plug and for connecting said telephone set to said plug and a plurality of other relays common to said incoming trunks, adapted to automatically control means for releasing said first individual relay to disconnect the operator's telephone and to reconnect the trunk conductors to the plug, and to operate the individual relay of the second trunk to disconnect the conductors thereof from the plug and to connect the telephone set to the plug when the second plug is inserted in another of said jacks before the first plug is removed.
- 5 15 20 25 30

In testimony whereof I have signed my name to this specification this 21st day of November, 1924.

GEORGE H. PETERSON.
